UNITED STATES PATENT OFFICE

CHESTER F. JOHNSON, OF DETROIT, MICHIGAN; DETROIT AND SECURITY TRUST COMPANY EXECUTOR OF SAID CHESTER F. JOHNSON, DECEASED

CARBURETOR

Application filed July 22, 1929. Serial No. 380,174.

This invention relates to carburetors for internal combustion engines and has special reference to a simplified and improved mixture controlling device embodying an accelerating fuel supply proportioned to the rapidity and extent of the throttle opening.

It is an object of this invention to provide an improved and simplified fuel metering control that incorporates a lean operating range adjustment with a richer maximum adjustment, together with means for variably increasing the duration and extent of an increased opening of the fuel metering control to provide extra fuel for accelerating demands which vary in accordance with the operation of the engine.

It is another object of this invention to provide an improved enrichening device for accelerating purposes that will be responsive to varying engine requirements as determined by the rapidity and extent of the opening movement of the throttle.

It is also an object of this invention to provide an improved and simplified carburetor embodying a single fuel nozzle with means for controlling the fuel supply there-to in accordance with the varying requirements of starting, maximum economy at part throttle, maximum power at full throttle and acceleration, together with adjustments controlling each of the different requirements.

Other and further important objects of this invention will be apparent from the disclosures in the specification and accompanying drawings.

The invention (in a preferred form) is illustrated on the drawings and hereinafter more fully described.

On the drawings:

Figure 1 is a side elevation of a carburetor with parts broken away to show the mixture control means.

Figure 2 is a side elevation of the opposite side of Figure 1, broken away to show the acceleration control means.

Figure 3 is a section on the line III—III of Figure 1.

Figure 4 is a section of a carburetor show-

ing the application of the present invention to an offset bowl type of carburetor.

Figure 5 is a transverse section through a carburetor embodying another form of this invention.

Figure 6 is a cross section of a carburetor wherein the acceleration fuel supply is based upon the control of an air bleed passage.

As shown on the drawings:

The general type of carburetor, chosen for illustrative purposes, comprises a body 10 having an auxiliary air supply housing 11 projecting from one side and a float bowl 12 mounted beneath the body in alignment with a mixing chamber passage 13, containing a throttle valve 14 on a shaft 15, and terminating in a mounting flange 16 for attachment to the engine. In Figures 1 to 3 and 6, a fuel passage 17 is centrally mounted in the float bowl and has a restricted nozzle 18 projecting into the throat 19 of a venturi shaped shell 20 forming the primary mixture supply, the air therefor entering a port 21 into a chamber 22 formed between the carburetor body 10 and the float bowl cover 10a.

The restricted nozzle 18 of the fuel passage 17 is provided of a capacity suitable for the maximum acceleration demand, being capable of supply much more than the quantity of fuel required for normal operation. In order to regulate the fuel supply for normal operation the lower end of the fuel passage 17 is obstructed by a movably mounted cone 23 which forms the equivalent of a fuel regulating needle valve, this valve being mounted on a lever 24 pivoted at 25. One end 26 of the lever 24 supports a sliding weight 27 which serves to keep the opposite end 28 of the lever in contact with a vertically mounted rod 29 in two sections placed end to end. The rod 29 is urged upwardly by a spring 30 into contact with an adjusting screw 31 in a lever 32, which screw forms the high speed adjustment for maximum power when the throttle is open. For maximum power at full throttle, a cam 33 is mounted upon the throttle shaft 15 in a position to force the lever 24 downwardly by acting through the rod 29 when the throttle shaft is rotated towards its full open

position. The lever 24 may be made, if desired, of thermostatic metals thereby making the fuel regulating needle responsive to temperature changes of the liquid in the fuel chamber.

At normal or intermediate positions of the throttle the cam 33 is turned out of contact with the lever, as shown in Figure 1 and a somewhat leaner mixture is obtained by the upward movement of the rod 29 which decreases the clearance between the needle valve or cone 23 and its seat in the end of the tube 17. In order to regulate the economizer adjustment the upward movement of the lever 24, when released by the cam, is limited by an adjusting screw 34 which forms the adjustment for the desired quality of fuel and air mixture for maximum economy throughout the partial throttle range. The point of transfer from the economical mixture range to the full throttle range is controlled by the position of the cam 33 on the throttle shaft 15, the cam being adjustably clamped on the shaft by a screw 35 in the split hub 36 of the cam.

A dash control is provided comprising a Bowden wire 37 the tube 38 of which is clamped at 39, the end of the wire 37 acting against the lever 32 to push it downwardly, thus pushing the needle valve 23 away from its seat through the medium of the lever 28 and the rod 29. This control gives an adjustably richer mixture for starting or driving before the engine has become warmed up to its normal operating temperature. It is to be noted that the first part of the dash control movement serves first to enrich that part of the operating range where the mixture is normally the thinnest.

In order to provide a momentary enrichment of the fuel and air mixture to compensate for the starving that would otherwise occur upon a sudden opening of the throttle to accelerate the engine, I provide a plunger 40, the lower end of which is chambered at 41 to receive the weight 27 in the chamber. A light spring 42 may be positioned, if desired, above the weight to increase the speed of movement thereby. The plunger 40 is connected by a link 43 to one of the holes 44 in a lever 45 mounted on the throttle shaft 15, the opening movement of the throttle lifting the plunger 40 and raising the weight 27 due to the suction in the chamber 41, thus allowing the lever 24 to swing counterclockwise, the needle valve 23 being thus withdrawn from the fuel passage 17 to produce an increased fuel supply the limiting amount of which is determined by the nozzle 18. As soon as the throttle is checked in its opening movement, the weight 27 slowly returns to its position into contact with the lever end 26, raising the lever into its normal operating position and cutting off the excess supply of fuel. The length of time required for the

return of the weight is dependent upon the freedom or clearance of the weight in the plunger and its distance of travel as determined by the connection of the link 43. The clearance determines the rapidity of fuel leakage into the chamber 41 as the lower end of the plunger is submerged in the fuel thereby making the movement of the weight sluggish. The position of the link 43 in the holes 44 of the lever 45 determine the extent of movement of the plunger for a full opening of the throttle, and the rapidity of movement of the throttle also modifies the period of the accelerating fuel charge, as a slow opening of the throttle might be such as to coincide in time with the downward movement of the weight in the plunger, in which case no additional opening of the fuel needle would result. This is a highly desirable feature, as the amount of accelerating fuel required varies in an inverse ratio to the acceleration performance demanded, which in turn is determined by the rapidity and extent of opening of the throttle valve.

The modification of Figure 4 is applied to a carburetor having an offset fuel bowl 46 with a bottom outlet 47 having a conduit 48 leading to the throat of the venturi 49 where the conduit is restricted by a nozzle 50 proportioned to restrict the maximum fuel delivery during acceleration. In this case the throttle lever 45, link 43, plunger 40 and weight 27 are arranged centrally of the fuel bowl and the lower end of the weight is formed as a valve 51 to control the outlet 47, a pilot 52 contacting an externally adjustable screw 53 to form the restriction for normal fuel delivery. When the weight 27 is lifted by an opening movement of the throttle 14 the delivery of fuel is materially increased being limited only by the nozzle 50 as in the previously described form of the invention.

Figure 5 discloses a modification of Figure 4 wherein the float bowl is concentric as in the first described form, so that the same reference numerals have been applied to the structures common to both. In this form the plunger member 54 is externally fluted to be guided within a passage 55, the flutes permitting the flow of fuel past the plunger. A weight 56 is slidably engaged in a chamber in the plunger and has its lower end formed as a valve 57 which controls the inflow of fuel at a valve seat 58, the weight carrying a pilot 59 which is engaged by an adjusting screw 60 as in the modification of Figure 4. The plunger 54 is linked directly to an offset lug 61 on the throttle 14 by a rod 62 passing through the venturi 20, the operation of this modification being essentially the same as in the preceding embodiments of the invention.

Figure 6 illustrates a modification of the structure of Figure 3 wherein the plunger 40 and weight 27 act to control a bent lever

63, one end 64 of which controls an air bleed aperture 65 opening into the fuel tube 17 above the fuel level in the float bowl. In this form of the invention the accelerating 5 fuel is limited by an externally adjustable needle valve 66, the tube 17 supplying a solid fuel stream to the nozzle 18 when the air bleed is closed for acceleration, while when the air bleed is open the air acts to ma- 10 terially reduce the fuel discharged through the nozzle under normal operating conditions and at the same time tends to break up the fuel stream to improve the operating economy.

15 It will thus be seen that in each of the modifications described I have provided an improved and simplified accelerating fuel supply cooperating with the normal fuel supply, the accelerating range and quantity of fuel 20 being subject to the rapidity and extent of throttle movement the fuel supply being dependent upon the suction existing within the carburetor rather than being pumped into the carburetor or manifold regardless of the 25 engine requirements.

I am aware that numerous details of construction may be varied through a wide range without departing from the principles of this invention, and I therefore do not purpose 30 limiting the patent granted, otherwise than necessitated by the prior art.

I claim as my invention:

1. In a carburetor, a mixing chamber having a throttle controlled mixture outlet, a fuel nozzle delivering fuel into said mixing chamber, a fuel chamber supplying said nozzle with fuel, a needle valve restricting the flow of fuel into said nozzle, a lever cooperating with said needle valve, a weight acting 40 against said lever to normally maintain said needle valve in position, and a plunger operated by said throttle and having a chamber normally enveloping said weight, where- 45 by the suction in said chamber is adapted to lift said weight upon a sudden upward movement of the plunger to increase the opening of said needle valve.

2. In a carburetor, a mixing chamber having a throttle controlled outlet, a fuel nozzle 50 delivering fuel into said mixing chamber, a fuel chamber supplying fuel to said nozzle, a needle valve restricting the supply of fuel to said nozzle, a pivoted lever supporting said needle valve and so balanced as to cause the needle valve to fall away from the nozzle, a weight acting against the lever to normally hold the same in position, a plunger partially enveloping said weight and adapted to lift the same by suction upon an 55 upward movement of said plunger, and means connecting said plunger to said throttle whereby an opening movement of said throttle will lift said plunger.

3. In a carburetor, a mixing chamber hav- 60 ing a throttle controlled outlet, a fuel nozzle 65

delivering fuel into said mixing chamber, a fuel chamber supplying fuel to said nozzle, a needle valve restricting the supply of fuel to said nozzle, a pivoted lever supporting said needle valve and so balanced as to cause the needle valve to fall away from the nozzle, means for adjusting the normal position of said lever, a weight acting against the lever to normally hold the same in position, a plunger partially enveloping said weight and adapted to lift the same by suction upon an upward movement of said plunger, and means connecting said plunger to said throttle whereby an opening movement of said throttle will lift said plunger.

4. In a carburetor, a mixing chamber having a throttle controlled outlet, a fuel nozzle delivering fuel into said mixing chamber, a fuel chamber supplying fuel to said nozzle, a needle valve restricting the supply of fuel to said nozzle, a pivoted lever supporting said needle valve and so balanced as to cause the needle valve to fall away from the nozzle, means operated by the throttle for shifting the normal position of said lever to en- 80 richen the mixture, a weight acting against the lever to normally hold the same in position, a plunger partially enveloping said weight and adapted to lift the same by suc- 85 tion upon an upward movement of said plunger, and means connecting said plunger to said throttle whereby an opening move- 90 ment of said throttle will lift said plunger.

5. In a carburetor, a mixing chamber having a throttle controlled outlet, a fuel nozzle delivering fuel into said mixing chamber, a fuel chamber supplying fuel to said nozzle, a needle valve in said fuel chamber controlling the entrance of fuel to said nozzle, said needle valve being so mounted as to fall away from said nozzle, a weight urging said needle valve towards said nozzle, adjustable means for limiting the upward movement of said needle valve, and means operated by the throttle adapted to lift said weight by suc- 100 tion imposed thereon by a sudden opening movement of said throttle.

6. In a carburetor including the fuel supply system and throttle thereof, a fuel nozzle having a capacity sufficient to discharge the maximum quantity of fuel required for accelerating purposes, means for restricting the delivery of fuel for normal operating conditions, an inertia element associated with said means, and means pneumatically connecting said element with the throttle to be operated by the sudden opening movement thereof to temporarily increase the fuel delivery from said nozzle.

7. In a carburetor including the float bowl and throttle thereof, a fuel nozzle delivering fuel from said float bowl and having a capacity sufficient for the maximum acceleration requirements, means for reducing the fuel capacity of said nozzle to a point satis- 125

- factory for normal operation, said means including a movable member held in position by an inertia element, and means connected to the throttle and cooperating with said inertia element to move the same in proportion to the rapidity and extent of the throttle opening movement whereby to temporarily increase the delivery of fuel from said nozzle for accelerating purposes.
10. 8. In a carburetor including the float bowl and throttle thereof, a fuel nozzle delivering fuel from said float bowl and having a capacity sufficient for the maximum acceleration requirements, means for reducing the fuel capacity of said nozzle to a point satisfactory for normal operation, said means including a movable member held in position by an inertia element, a plunger partially enveloping said element and adapted to move the same to an extent, dependent upon the rapidity of movement of said plunger, and means connecting said plunger to said throttle whereby an opening movement of said throttle will lift said plunger.
15. 9. In a carburetor including the float bowl and throttle thereof, a fuel nozzle delivering fuel from said float bowl and having a capacity sufficient for the maximum acceleration requirements, means for reducing the fuel capacity of said nozzle to a point satisfactory for normal operation, said means including a movable member held in position by an inertia element, a plunger partially enveloping said element and adapted to move the same upon movement of said plunger, and means connecting said plunger to said throttle whereby an opening movement of said throttle will lift said plunger.
20. 10. In a carburetor, including a mixing chamber, a throttle and means forming a fuel supply, a metering nozzle delivering fuel from said fuel supply to said mixing chamber, means operable by throttle movement to vary the fuel delivery capacity of said metering nozzle, and accelerating means operated in unison with said throttle and embodying an inertia element temporarily affected by differential pressure upon a sudden opening of the throttle, to alter the normal control of the fuel delivery from said metering nozzle.
25. 11. In a carburetor, including a mixing chamber, a throttle and means forming a fuel supply, a metering nozzle delivering fuel from said fuel supply to said mixing chamber, means to vary the fuel delivery capacity of said metering nozzle, and accelerating means operated in unison with said throttle and embodying an inertia element temporarily affected by differential pressure upon a sudden opening of the throttle to alter the fuel delivery from said metering nozzle.

In testimony whereof I have hereunto subscribed my name at Detroit, county of Wayne, Michigan.

65 CHESTER F. JOHNSON.
